[57] CLAIM

The ornamental design for a head part for lid opener, as shown.

DESCRIPTION

FIG. 1 is a bottom front and side perspective view of a head part for lid opener showing my new design; FIG. 2 is a left side elevational view thereof, the side opposite being a mirror image; and, FIG. 3 is a top side and front perspective view thereof. The rear elevational view of the shaft is plain and unadorned.

FIG. 1

FIG. 2

FIG. 3
